PERCIVAL J. TOWNSEND, OF REDWOOD CITY, CALIFORNIA.

ELECTRIC FIRELESS COOKER.

1,416,527.

Specification of Letters Patent. Patented May 16, 1922.

Application filed May 25, 1920. Serial No. 384,132.

To all whom it may concern:

Be it known that I, PERCIVAL J. TOWNSEND, a citizen of the United States, residing at Redwood City, in the county of San Mateo and State of California, have invented new and useful Improvements in Electric Fireless Cookers, of which the following is a specification.

This invention relates to cooking devices and has for its object the provision of a fireless cooker in which the necessary initial heat is provided by an electric heating coil embedded within a slab of soapstone, this heating member being disposed upon a base rising from which and detachably engaged upon which is a hood formed to retain heat, the construction of the device being such that after the slab of soapstone is thoroughly heated by the resistance coil therein, the current may be cut off and the heat stored within the slab will be sufficient to complete the cooking.

An important and more specific object is the provision of a device of this character which includes a base upon which the heating coil and the hood are disposed, this base being peculiarly constructed whereby water of condensation forming upon the inner surface of the walls of the hood may run down and be retained within a circumferential channel and thereby form a seal between the hood and the base.

Another object is the provision of a device of this character in which the hood is carried by a flexible member trained over suitable pulleys and having a counterbalancing weight whereby the hood may be very quickly and easily lifted when desired to permit inspection of the articles being cooked or to permit their removal.

An additional object is the provision of a device of this character which will be simple and inexpensive in manufacture, highly efficient and economical in use, durable in service, and a general improvement in the art.

With the above and other objects and advantages in view the invention consists in the details of construction to be hereinafter more fully described and claimed, and illustrated in the accompanying drawings in which—

Figure 1 is a side elevation of my device, Figure 2 is a front elevation,

Figure 3 is a longitudinal sectional view 55 therethrough, showing the hood in raised position,

Figure 4 is a top plan view of the heater member,

Figure 5 is a detail sectional view 60 therethrough, and

Figure 6 is a bottom plan view.

Referring more particularly to the drawings, I have shown my device as comprising a base 10 which is formed preferably of sheet metal and hollow, the interior being packed with any suitable heat insulating material. This base is preferably circular in shape and has its outer edge reduced in thickness, as shown at 11, whereby the central portion 70 will extend upwardly and be disposed in a higher plane than the portion 11. It will be understood that this base may be secured upon or set upon a table or shelf, though in the drawings I have shown it as supported 75 by a bracket 12 extending from a vertical wall 13.

Disposed upon the base 10 is a hood designated broadly by the numeral 14 and this hood is formed of outer and inner metallic 80 shells 15 and 16 spaced apart and having the space therebetween filled with a suitable heat insulating packing 17. The lower or open end of this hood seats upon the reduced portion 11 of the base 10, as clearly shown, and 85 the effect is such as to provide a circumferential channel between the inner periphery of the hood and the outer periphery of the central or thicker portion of the base. This channel is designated by the numeral 90 18. It will be observed that formed at the outer edge of the reduced portion 11 is an upstanding flange 19 which extends outwardly of and engages against the outer periphery of the hood.

Secured upon the upper end of the hood is an eye 20 with which is connected one end of a flexible member 21 which is trained about a pulley 22 mounted on the bracket 23 carried by a tubular guide 24 secured to the wall 13. Adjacent the pulley 22 the flexible member 21 enters the tubular guide 24 and extends therethrough and beyond the other end thereof and this projecting end carries a counterbalancing weight 25.

The heater is designated by the numeral 26 and this heater is formed from a circular slab or disk 27 of soapstone which has its

upper surface cut, as clearly shown in Figure 4, to provide a plurality of channels 28 which connect or communicate, as shown. Disposed within these channels is a heating coil 29 formed of wire of suitable resistance arranged in serpentine form so as to cover the maximum area of the surface of the slab. The ends of the coil pass through holes 30 in the slab and then extend along grooves 31 in the underside thereof and are connected with suitable binding screws 32 to which feed wires from any suitable source of current may be connected. If found advisable, and it probably will be, the channels 28 in the slab may be filled with any suitable paste or cement in order to protect the coil 29.

In the use of the device the heater 26 is disposed upon the top of the base 10 and the articles of food to be cooked are placed upon the heater and if they are of a moist nature it is obvious that they should be placed in a suitable receptacle. By using receptacles of the clover-leaf type it will be obvious that several different articles may be cooked at the same time. After the receptacle containing food or other material is placed upon the heater, the hood 14 is lowered and current is turned on through the coil 29. The heat generated by this coil will quickly heat the slab 27 and as soon as the same is thoroughly heated the current may be cut off and the heat continuing to emanate from the slab will serve to cook the material in exactly the same manner as cooking is carried on in a fireless cooker, it being quite apparent that my double walled hood will effectually retain the heat given off by the slab. In case articles are to be baked, it is quite evident that they may be placed directly upon the slab 40 and the receptacle omitted, if desired.

When it is desired to cook articles more rapidly it is obvious that the current need not be cut off and that the device may be then used simply as an electric cooker, either with or without the hood, as preferred.

It will be noted that the connection or joint between the hood 14 and base 10 is an important feature of my construction. When any food is cooked in this device or in any 50 similar device, it is well known that a certain amount of steam will condense upon the inner surface of the hood and will conse-

quently trickle down. By my construction in which I reduce the thickness of the outer portion of the base and leave the slight upstanding flange 19 at the periphery thereof, I prevent this condensed steam which trickles down from getting onto the central portion of the base or the heater thereon. In my construction the circumferential channel 18 receives this trickle of condensation and the flange 19 retains a certain amount of this water so as to form a water seal which provides a very effective seal for preventing leakage of heat between the hood and the base. At the same time it will be noted that the flange 19 is of less height than the central portion of the base so that the water of condensation may overflow and escape before it could back up a sufficient extent to injure the heating coil upon the base.

While I have shown and described the preferred embodiment of my invention, it is of course to be understood that I reserve the right to make such changes in the form, construction, and arrangement of parts as will not depart from the spirit of the invention or the scope of the subjoined claims.

Having thus described my invention, I claim:

1. A device of the character described comprising a base, heating means upon said base, and a removable hood seating upon the base and formed as a heat retaining member, the outer portion of said base being circumferentially recessed to provide a seat for the lower end of the hood, and the extreme periphery of the base having an upwardly extending flange of less height than the central portion of the base and disposed outwardly of the hood.

2. A device of the character described comprising a supporting bracket, an upwardly extending tubular guide associated therewith, a roller carried by the upper end 95 of said guide, a base mounted upon said bracket, a hood seating upon said base, heating means upon said base, a flexible member connected with said hood, trained about said roller, extending through said tubular guide, 100 and a counterbalancing weight on the lower end of said flexible member.

In testimony whereof I affix my signature.
PERCIVAL J. TOWNSEND.
